UNITED STATES PATENT OFFICE.

LOUIS M. WOOD, OF NEW YORK, N. Y., ASSIGNEE, BY MESNE ASSIGNMENTS, TO SPEED-O-MULTIPLE VALVE LIFTER CORPORATION.

VALVE-SPRING LIFTER.

Application filed February 28, 1922. Serial No. 539,993.

To all whom it may concern:

Be it known that I, LOUIS M. Wood, a citizen of the United States, and a resident of the city of New York, borough of Manhattan, in the county and State of New York, have invented a new and Improved Valve-Spring Lifter, of which the following is a full, clear, and exact description.

This invention has relation to devices for lifting or compressing the valve springs of internal combustion motors and contemplates as its general object to provide improved means for lifting valve springs and facilitating the operation of removing and grinding the valves.

A further object of the present invention is to provide an efficient, practicable, relatively, inexpensive, and quick operating device for simultaneously compressing a multiplicity of springs whereby the valves and retaining springs may be readily removed, and for retaining the springs under compression until the grinding operation is completed and the valves and pins reassembled.

Furthermore the invention contemplates a device of the character described which includes means automatically operable upon compression of the valve springs to retain said springs compressed whereby the operation of removing the retaining pins, removing and inserting the valves and reinserting the retaining pins may be accomplished while the springs are retained in their compressed condition.

A further object of this invention is to provide a multiple valve spring lifter comprising a lifting member co-acting with the valve spring and wherein such member is positively guided with relation to the valves in an improved and efficient manner.

A further object of this invention is to provide a valve spring lifter including a vertically shiftable lifting member adapted to coact with the valve springs, and wherein said member is lifted by cam action.

With the above recited and other objects in view, the invention resides in the novel construction set forth in the following specification, particularly pointed out in the appended claims and illustrated in the accompanying drawings; it being understood that the right is reserved to embodiments other than those actually illustrated herein to the full extent indicated by the general mean-

ing of the terms in which the claims are expressed.

In the drawings—

Figure 1 is a fragmentary transverse sectional view through a motor taken approximately on the line 1—1 of Fig. 2 and illustrating the valve spring lifter in operative relation thereto.

Fig. 2 is a sectional plan view thereof taken approximately on the line 2—2 of Fig. 1.

Fig. 3 is a face view of the spring engaging and retaining device removed.

Referring to the drawings wherein I have illustrated a preferred form of my invention it will be seen that the motor block A of the engine is provided with the usual valve spring chamber B which is normally closed by a cover plate, not shown. The cover plate is normally retained in place by means of either a lag screw C, as illustrated, or a stud bolt. The valves D are provided with valve stems E which extend into the valve spring chamber B and are provided with the usual removable retaining pins F. The pins F coact with spring seats G into which the lower ends of the several valve springs H are seated. The opposite ends of the springs engage on upper wall of the valve spring chamber, the springs normally causing the seating of the valves. The lower wall of the chamber B is provided with upstanding valve lifter guide sleeves I through which the valve lifters J are movable when actuated by the cams for lifting the valves against the action of the spring.

It will be noted that the valve spring chamber B is located within a housing or casing comprising a rear wall L and forwardly extending end walls M, the latter adapted to form a guide for the valve spring lifter bar hereinafter described.

The present valve spring lifter or compressing device comprises a lifting bar or member 10 and a lifting lever, 11. The lifting member 10 is provided on its inner side with a plurality of valve spring seat engaging forks or members 13 and provided at its opposite side with depending legs 14 pivotally connected thereto for transverse swinging movements. Each leg is provided with a pair of inwardly projecting studs 15 and 16 with which a leaf spring 17 is engageable for respectively effecting inward or outward lateral swinging of the leg. The

lower extremity of each leg is notched or cutaway as at 18 for a purpose to be hereinafter set forth. The bar 10 is provided with one or a number of vertically disposed slots 19 to correspond to the number of lag screws or stud bolts C with which the particular type of motor is equipped. The lifting lever 11 is in the present instance provided with a bifurcated or forked inner 10 extremity comprising a pair of prongs 20, each of which may be provided at its free end with a transverse pin 21 extending from the opposite sides thereof.

In operation of the device the nut 12 on 15 the outer end of the lag screw or bolt C may be removed for the purpose of removing the cover plate, and the bar 10 placed in position with the bolt C extending through the guide slot 19. The nut 12 is then 20 screwed on to the end of the bolt C, the forks 13 extending under the valve spring seat G and embracing the valve stem E. The leaf springs 17 are engaged with the outer studs 16 of each leg and the prongs 20 of 25 the lever are inserted into the chamber to cause the opposite extremities of the pins 21 to engage behind the valve lifter guide sleeves I. An upward movement of the outer end of the lever 11 will effect the 30 engagement of the prongs with the under side of the bar 10 thereby lifting the bar and compressing and lifting the valve springs H. It will be noted that the lifting bar 10 in 35 this instance is provided with projecting portions which overlap or engage the front edges of the end walls M of the housing and hence the lifting bar by virtue of these end guide portions is guided thereby in a vertical plane, thus causing the member 13 40 to be positively shifted in a vertical plane. The guide slot 19 centers the lifting members 13 with relation to the valve spring retainers G, and acts as a guide for restricting any material endwise movement of the bar 10 45 without, at the same time causing any pressure to be exerted upon the bolt C. When the bar or plate 10 has been lifted a sufficient distance to bring the notched or cut-away lower extremities of the legs in registration 50 with the upper edge of the lower wall of the valve spring chamber B, the springs 17 will swing the legs or locking members 14 inwardly into engagement with said edge, thereby retaining the springs H under compression. The lifting lever 11 may then be 55 removed and the operator may readily remove the retaining pins F and the valves D. After the grinding operation the valves are reinserted and the pins F replaced. 60 The lever 11 is again placed in position and the springs 17 are then engaged with the inner studs 15 whereby an initial lift of the lever will cause said springs to swing the legs 14 outwardly, thereby unlocking the 65 lifting bar. The expansion of the valve

springs will lower the lifting bar and reseat the valve spring seats on the retaining pins F.

It will be observed that as the prongs 20 of the lifting lever 11 engage the under side of the bar 10 and elevate the same, the latter slides over the upper edges of the prongs. Thus, the action of elevating the bar 10 through the lever 11 is a cam action, and the upper edges or surfaces of prongs or projections 20 act as cam surfaces. As a result of this cam action the power necessary to compress the springs is considerably reduced.

I claim:

1. A valve spring lifter comprising a bar adapted to engage the under sides of a plurality of valve spring seats, means for lifting said bar and compressing the springs, and resilient locking means carried by said bar for retaining the same in lifted position and the springs under compression.

2. A valve spring lifter comprising a lifting bar adapted to be detachably associated with a motor, means engageable with the motor and the under side of said bar for raising the same, and means carried by said bar and engageable with the motor for retaining said bar in its elevated position.

3. A valve spring lifter comprising a lifting bar adapted to be detachably associated with a motor, means engageable with the motor and said bar for raising the bar, means carried by said bar and engageable with the motor for retaining said bar in its elevated position, said means comprising a pair of pivoted supporting legs, and means for swinging the same.

4. A valve spring lifter comprising a lifting bar adapted to be detachably associated with a motor, a plurality of valve spring seat engaging members projecting therefrom, locking members pivoted to said bar, resilient means engaging said members for swinging the same, and means for lifting the bar to compress the valve springs.

5. In a motor having a valve spring chamber and a cover plate retaining bolt, means for lifting and retaining the valve springs under compression and comprising a bar having a guide slot embracing said retaining bolt, means carried by said bar and adapted to engage the under sides of a plurality of valve spring seats, means for elevating said bar and automatic means carried by the bar for supporting and retaining the bar in elevated position.

6. A valve spring lifter adapted to be used with a motor having a valve spring housing and comprising a lifting member provided at opposite ends thereof with guide portions adapted to overlap the housing when the lifting member is located in operative position, and means engageable with the motor and underside of said member

and when operated having a shiftable engagement with one thereof for elevating said member.

7. In a valve spring lifter, the combination of a lifting bar having means for operating against a plurality of valve springs, means for elevating said bar, and means carried by said bar independently of said last means for maintaining the same in elevated 10 position.

8. In a valve spring lifter, the combination of a lifting bar having means for operating against a plurality of valve springs, lever means for elevating said bar, and 15 means carried by said bar independently of said last means for maintaining the same in elevated position.

9. In a valve spring lifter the combination of a lifting member having means extending beneath three or more valve springs for operating thereagainst, means engageable with the motor and said member for lifting the same, and means carried by said member for guiding the same against 20 25 placement relatively to the valve springs during operation.

10. A valve spring lifter for a motor having a valve spring housing, a plurality of valves and springs and a housing stud or 30 bolt, and comprising means for lifting said springs under tension, said means comprising a member having a guide slot adapted to embrace said bolt.

11. A valve spring lifter for a motor having a valve spring housing, a plurality of 35 valves and springs and a housing stud or bolt, and comprising means for lifting said springs under tension, said means comprising a member having a guide slot adapted to embrace said bolt, and said member engaging said housing in front of the valves 40 and guided thereby.

12. A valve spring lifter for a motor having a valve spring housing, a plurality of 45 valves and springs and a housing stud or bolt, and comprising means for lifting said springs under tension, said means comprising a member having a guide slot adapted to embrace said bolt, and cam means for 50 operating said member.

13. In a valve spring lifter, a shiftable lifting member having means for operating against three or more valve springs, means for shifting the same to simultaneously 55 compress all the springs, and shiftable locking means engaging said member for maintaining the same in shifted position.

14. In a valve spring lifter, the combination of a shiftable lifting member having 60 means for operating against at least three or more valve springs, means for shifting the same to simultaneously compress all the

springs, and shiftable self-locking means extending beneath said member for maintaining the same in shifted position.

65

15. In a valve spring lifter the combination of a shiftable lifting member for a plurality of valve springs, said member in operative position having a vertically extending guide slot and depending locking 70 members.

16. In a valve spring lifter the combination of a vertically shiftable lifting member for a plurality of valve springs, said member having a vertical guide slot and spring controlled locking supports.

75

17. In a valve spring lifter the combination of a member having means projecting therefrom for operating against a plurality of valve springs, and means for lifting said member, said member having a pair of guide means cooperating with the engine, one for guiding the member against transverse movement and the other for guiding the member against endwise movement.

80

18. In a valve spring lifter, the combination of a shiftable lifting member having means for operating simultaneously against three or more valve springs, and lever means slidingly engaging the underside thereof for lifting said member.

85

19. In a valve spring lifter, the combination of a shiftable lifting member extending lengthwise in front of three or more valve springs and also beneath the same for operating thereagainst, and means supported independently thereof for lifting said member by cam action.

95

20. In a valve spring lifter, the combination of a shiftable lifting member extending lengthwise in front of three or more valve springs and also beneath the same for operating thereagainst, and means slidingly engaging the underside of said member for lifting the same.

100

21. In a valve spring lifter, the combination of a shiftable lifting member extending lengthwise in front of three or more valve springs and also beneath the same for operating thereagainst, and means engageable with the motor and underside of said member and when operated having a sliding engagement with one thereof for elevating said member.

110

22. A valve spring lifter comprising lifting means having means adapted to extend beneath three or more valve springs for operating thereagainst when said lifting means is elevated, and means shiftable beneath said lifting means for maintaining the same in elevated position and all of said valve springs under compression.
